UNITED STATES PATENT OFFICE.

BERTRAM JOHN TURNER, OF NEW SOUTHGATE, LONDON, ENGLAND.

MAGNETO-ELECTRIC MACHINE.

1,301,524.

Specification of Letters Patent. Patented Apr. 22, 1919.

Application filed August 25, 1917. Serial No. 188,241.

To all whom it may concern:

Be it known that I, BERTRAM JOHN TURNER, a subject of the King of Great Britain and Ireland, residing at 62 Warwick road, New Southgate, London, N., England, have invented certain new and useful Improvements Relating to Magneto-Electric Machines, of which the following is a specification.

10 This invention relates to magneto-electric machines of the kind commonly used for ignition in internal combustion engines.

The contacts for such magneto-electric machines frequently operate in situations where they are exposed to the deposits of foreign matter and the invention has for its object to shield the plunger contact with a view to prevent or minimize such deposits.

According to the invention the fitting is 20 provided with an insulating tube the lower end of which is outwardly extended to form a shield.

The invention is illustrated by way of example in the accompanying drawings in 25 which—

Figure 1 represents in elevation a contact fitting according to the invention.

Fig. 2 is a sectional elevation corresponding to Fig. 1, and

30 Fig. 3 is a corresponding plan.

In carrying the invention into effect as illustrated in the accompanying drawings, the metal tubular contact fitting *a* is provided at its extremity with a screw threaded 35 pin *b* upon which is mounted the contact screw *c* and the tubular fitting *a* is mounted in position by means of a flange *d* of vulcanized fiber or other suitable insulating material.

40 According to the invention a tubular sleeve *e* of vulcanite or other suitable insulating material is provided as a plunger having secured within it at one end a plug *f*

which is formed above and below with grooves *f*¹ *f*² for the reception of the ends 45 of the respective spiral springs *g* and *h*. The spiral spring *g* serves the purpose of outwardly forcing the insulating tube *e* and of carrying the tube by the engagement with the groove *f*¹ in the plug *f*. The spiral 50 spring *h* is mounted within the insulating tube *e* and at one end engages the groove *f*² in the plug *f* while at the other the spiral spring *h* engages the groove *i*¹ provided in the upper part of the cylindrical contact 55 pin *i*. The lower end of the insulating tube *e* protrudes downwardly and outwardly to cover over and to shield the lower end of the contact pin *i*.

The spiral spring *h* within the insulating 60 tube *e* outwardly forces the contact pin *i* into contact with the metal contact plate or surface while the insulating tube *e* surrounding the contact pin *i* is independently pressed down so as thus to cover up and to 65 shield the metal contact plate so that thus the contact pin *i* and the metal plate are shielded without lessening the effectiveness of the contact.

The invention is more especially applica- 70 ble to magneto-electric machines of the Ford type but it is of general application.

I claim:—

In magneto-electric machines, a contact fitting, comprising an insulating tube, a 75 spiral spring by which said insulating tube is outwardly thrust, a contact pin carried at the end of the said insulating tube, a second spiral spring by which the said contact pin is outwardly thrust, said insulating tube being provided with an extending flange at 80 its outer end to cover and to shield the contact pin and the contact surface, substantially as described.

BERTRAM JOHN TURNER.
